UNITED STATES PATENT OFFICE.

HARRY M. SLOAN, OF CHICAGO, ILLINOIS.

STREET-CAR.

1,216,003.

Specification of Letters Patent. Patented Feb. 13, 1917.

Application filed October 21, 1907. Serial No. 398,517.

To all whom it may concern:

Be it known that I, HARRY M. SLOAN, a citizen of the United States, residing at Chicago, in the county of Cook and State of Illinois, have invented certain new and useful Improvements in Street-Cars, of which the following is a specification.

My invention relates to improvements in street cars, and has for its general object 10 to provide a construction to facilitate the handling of passengers and the conductor's work of collecting fares.

A further object of my invention is to provide a car so constructed that the movement 15 of passengers in entering and leaving the car will necessarily be such as to minimize confusion and delay and may be controlled to an effective degree by the conductor, through the agency of gates and doors operated from a conductor's station at a suitable point upon the car.

Another object of my invention is to provide simple and efficient mechanism for effecting such control; and yet other objects 25 will become apparent to those skilled in the art from the following description taken in conjunction with the accompanying drawings, wherein I have illustrated a simple embodiment of the invention.

30 In the drawings;

Figure 1 is a transverse section through the rear platform of a car;

Fig. 2 is a sectional detail of car door moving apparatus;

Fig. 3 is a plan view of the rear platform and end of a car body; and,

Fig. 4 is a detail of the car door and platform gate controlling mechanism.

Throughout said figures like numerals of 40 reference refer always to like parts.

The car as a whole is structurally divided above its floor into two compartments. In the drawing 10 indicates in general a car body constituting one compartment, and 11 45 the rear platform of the car, constituting another compartment, such platform being preferably of larger size than has customarily been provided in street cars.

12 and 13 indicate respectively separate 50 entrance and exit openings in the end wall of the body, constituting independent passageways affording communication between the platform and the body of the car, such openings or door-ways being preferably at

opposite sides of the car with the exit doorway on the side of the platform nearest the car step. Between the openings or doorways 12 and 13 I preferably provide a casing or abutment 14, and for control of the entrance and exit opening I provide individually shiftable barriers or doors 15 and 16 respectively, which are preferably sliding doors arranged to slide into or out of the casing 14.

For communication with the street one 65 side only of the platform, usually the right side, is provided with a step or steps 17 leading to the ground, and the space opening to the steps is divided into separate immediately contiguous entrance and exit openings, 70 18 and 19, preferably by an upright post 20.

21—21 indicate companion gates or movable barriers controlling the exit opening 19 to the street such gates being preferably outwardly opening members meeting at the 75 center of the opening 19 and respectively pivoted on the upright 20, and a vertical rod 20' adjacent the end of the car body.

Upon the platform, preferably the area 80 thereof directly in rear of the middle casing 14 of the rear end of the car body, I provide a conductor's station, which I prefer shall be to a suitable degree separated from the balance of the platform, and to this end I provide a railing or other suitable division 85 wall, 22, which preferably extends from the edge of the casing 14 adjacent the doorway 13, a suitable distance rearward and thence transversely of the car in an inward direction, to substantially longitudinal abutment 90 with the edge of the doorway 12, preferably on substantially the transverse line of the upright 20.

The space thus partially inclosed, and indicated at 23, I term the conductor's station, 95 and by the means described I provide a place for the conductor where he may be free from interference of passengers and may conveniently collect the fares of entering passengers and operate the mechanism under 100 his control.

The gates 21 and preferably also the doors 15 and 16 are arranged for control in opening and closing from the conductor's station 23, the system of control employed 105 preferably making the gates 21 operable only from the conductor's station, and placing it within the power of the conductor to

lock either door 15 or 16 against being opened by the passengers although permitting them to open such doors under ordinary conditions.

5 In the specific construction illustratively shown the door movements are controlled from a crank stand 25 provided within the confines of the conductor's station, such stand in the embodiment shown comprising 10 a vertical standard or casing having concentrically arranged therein a central shaft 26, and two surrounding sleeves, or hollow shafts, 27 and 28, such shafts being at their upper ends provided respectively with super- 15 posed crank wheels or handles 26', 27' and 28', of successively increasing diameter. The shaft 26 and the surrounding rotatable sleeves or hollow shafts extend below the platform 11 of the car, the outer shaft member being the shortest and the inner shaft 26 being the longest in projection below the floor. Upon the extremity of shaft 26 I provide a crank lever 30, connected by link 31 with a cross head 32, the opposite extremities of which have connected thereto 20 links 33 respectively connected with cranks 34 respectively secured to the upright rods 20, 20' carrying the gates 21. It will be apparent that partial rotation of handle 26' 25 opens or closes the gates.

The hollow shaft 27 is at its lower end suitably connected with the body-entrance closing door 15, to move the latter, such connections as herein shown comprising a 30 sprocket wheel 35 geared by a chain 36 to a sprocket 37, mounted upon the lower extremity of vertical shaft 38 extending up through the casing 14, and at its upper end provided with a pinion 39 meshing with 35 the rack bar 40 suitably secured to the door, preferably adjacent its point of sliding support. Obviously rotation of handle 27 through the gearing connection rotates the pinion 39 to move the rack and correspondingly the door in appropriate direction, so 40 that the conductor may open and close the door without leaving his station. I prefer further that mechanism be provided whereby the conductor may lock the door 45 against opening, and to this end I provide upon the shaft 27 a ratchet 42, for coaction with which I arrange a pawl 43 mounted upon a vertical shaft extending through the platform 11 and at its upper end carrying 50 a tripping member or foot piece 44. Whenever the conductor desires to lock the door to prevent ingress of passengers into the body of the car he moves the foot member 44 in appropriate direction to throw the 55 pawl 43 into engagement with the ratchet 42, where it remains until moved back to disengaged position by the conductor, and after such release the door may be opened by the passenger.

60 65 For operating the body-exit closing door

16 I provide corresponding mechanism, the sprocket upon the shaft 28 being indicated by numeral 42' and the remaining connections with the door, similar to those above described, being indicated by like ordinals of references differentiated by the exponent prime ('').

70 For the protection of passengers against injury by the doors 15 and 16, I provide on each side of the jamb or frame of each body door a grab-handle 45 in such arrangement that the hand of a passenger grasping such handle is not in the path of movement of the door.

75 In the operation of the car the conductor stands at his station 23, and at any stopping point where the passengers desire to leave the car he opens the door 16 and the gate 20 both clearing an exit way through the openings 13 and 19. Those waiting to board the car may freely enter through the unobstructed opening 18, and naturally group themselves about that opening, leaving free for debarking passengers space to alight. Passengers may, therefore, get off while 80 others are boarding the car without confusion or delay.

85 When all the leaving passengers have passed through the gates 21, the conductor closes the gates 21 and may close and latch the door 16 thereby insuring that no passengers will enter the car through the exit opening. Passengers entering the car pass through the unobstructed entrance passage 18 on to the enlarged platform, and in order 90 to reach the entrance opening 12 in the body of the car they must pass by the station of the conductor, so that he is easily able to collect their fares. If the work attending to the passengers leaving the car, or the 95 crowding of entering passengers make difficult the collection of fares, the conductor can positively prevent passengers who have not paid their fares from entering the body of the car by latching the door 15 in closed position until he has completed his collection.

100 It will be apparent that the arrangement described leaves unobstructed a passage-way from the car-body-exit doorway 13 to the 105 rear portion of the platform so that in the event any entering passenger should by mistake crowd in through the opening 19, while the gates 21 are open, such passenger may be directed into the proper entrance way 110 past the conductor's station without the necessity of getting off the car or dodging any obstruction, and further passengers who have been riding on the rear platform and desire to debark may get off at the proper 115 exit opening 19, avoiding interference with passengers entering through their proper entrance 18.

120 125 130 It will be obvious that if mere control of the doors 15 and 16 to prevent them from

being opened is desired, the moving mechanism may be dispensed with and only a suitable latching mechanism retained, but for many purposes conductor's control of the 5 opening and closing of the doors is desirable.

While I have herein described in some detail 10 a specific embodiment of my invention for purposes of simple illustration thereof it will be apparent to those skilled in the art that numerous changes in the specific embodiment might be made without departure from the spirit and scope of my invention and I do not desire to be understood as limiting my invention to the specific construction shown 15 in the drawings.

Having thus described my invention, what I claim and desire to secure by Letters Patent, is:

20 1. In a car a body, a platform extending across the end of the body, steps extending along one side of the platform, means adjacent the steps dividing the open side into separate entrance and exit openings to the ground, side by side, and both communicating with the steps, a closure for the exit opening, separate exit and entrance openings from the platform to the body of the car, means partially segregating from 25 the balance of the platform a conductor's station located between said separated openings to the body, and means accessible from said conductor's station for opening the closure for the exit to the ground.

30 35 2. In a car, a platform having separate entrance and exit openings to the ground and separate entrance and exit openings to the body of the car, closures for the two openings to the body of the car and an independent closure for the exit opening to the ground, and means operable from the platform for opening and closing the last said closure.

40 45 3. In a car, a platform having separate entrance and exit openings to the ground, and separate entrance and exit openings to the body of the car, a closure for the entrance to the body of the car, a closure for the exit to the ground, means partially segregating from the balance of the platform a conductor's station, means operable from 50 said conductor's station to open and close the said exit closure, and means operable from said station to prevent the opening of the closure for the entrance to the car body.

55 60 4. In a car, a platform having separate entrance and exit openings to the ground at one side, the exit opening being nearest the body of the car, and separate entrance and exit openings to the body of the car, the exit opening being nearest the side openings of the platform, a railing extending from a point adjacent the inner side of the exit opening from the body rearward and thence 65 transversely toward the entrance opening to

the body, and closures for the entrance and exit openings to the body and means operable from the conductor's station to control said closures.

5. In a car, a platform having separate entrance and exit openings to the ground, and separate entrance and exit openings to the body of the car, a railing partially defining from the balance of the platform a conductor's station, closures to the entrance and exit openings to the body of the car, a closure for the exit opening to the ground, and means operable from the conductor's station for opening and closing said several 70 75 closures.

6. In a car, the combination with a sliding door, means for positively closing said door and a frame therefor, of a pair of grab-handles extending from the edge of the frame with which the door coacts when closed, such grab-handles respectively extending in parallelism to the edges of the door-frame at a suitable distance from the path of travel of the door to prevent the hand of the passenger grasping them from 80 85 being struck by the door.

7. A street car having a platform with steps along one side thereof, a barrier dividing the steps into entrance and exit passages, a side door controlling at least one of said 90 95 entrance and exit passages, and a distant control device having operating connections for the side door at the steps.

8. A street car having an entrance and exit portion provided with a side step, means 100 at the step dividing it into entrance and exit passages, a barrier on the entrance and exit portion arranged to aid in separating the incoming and outgoing passengers, a side door controlling at least one of the entrance 105 and exit passages from the step, a control device adjacent to the barrier, an operating connection between said control device and said side door.

9. A street car having an entrance and 110 exit portion provided with a side step, a vertical post adjacent to the step and forming entrance and exit passages therefor, a side door controlling at least one of said entrance and exit passages, a barrier on the 115 entrance and exit portion arranged to assist in separating the incoming from the outgoing passengers, a controlling device adjacent to the barrier and operating connections between said control device and the 120 side door.

10. A street car having an entrance and exit portion with a side step, a vertical post adjacent to the step forming entrance and exit passages, a side door, a barrier on the 125 platform arranged to assist in separating the incoming from the outgoing passengers, a control device at the prepayment point, and operating connections between said control device and said side door. 130

11. A street car having an entrance and exit portion with a side step therefor, a vertically extending barrier adjacent to the step and arranged to form entrance and exit passages, a side door controlling at least one of said entrance and exit passages, a control device removed from the door and adjacent to the prepayment point, and operating con-

nections between said control device and said side door.

In testimony whereof I hereunto set my hand in the presence of two witnesses.

HARRY M. SLOAN.

In the presence of—

GEO. T. MAY, Jr.,

MARY F. ALLEN.
